UNITED STATES PATENT OFFICE.

MARTIN CHRISTENSEN, OF RACINE, WISCONSIN, ASSIGNOR TO CHRISTENSEN MACHINE CO., OF RACINE, WISCONSIN, A CORPORATION OF WISCONSIN.

SIGNATURE-FEEDING MECHANISM FOR BOOK-STITCHING MACHINES.

1,400,725.

Specification of Letters Patent. Patented Dec. 20, 1921.

Application filed December 18, 1919. Serial No. 344,696.

To all whom it may concern:

Be it known that I, MARTIN CHRISTENSEN, a citizen of the United States, and resident of Racine, in the county of Racine and State 5 of Wisconsin, have invented new and useful Improvements in Signature-Feeding Mechanism for Book-Stitching Machines, of which the following is a description, reference being had to the accompanying drawings, which are a part of this specification.

The present invention relates to certain new and useful improvements in signature handling machines and refers more particularly to the mechanism for feeding the collected groups of signatures to the stitchers or binders and away from the same to the delivery mechanism.

The primary object of the present invention is to provide means for positively feeding groups of signatures to a stitcher.

A further object of this invention is to provide a signature feeding mechanism adapted to feed groups of signatures to a stitcher and away from the stitcher after 25 they have been operated upon by the stitcher.

A still further object of the present invention is to provide a feeding mechanism for book-stitching machines which will be positive in operation, and which will be of 30 simple construction, all things considered.

With the above and other objects in view which will appear as the description proceeds my invention resides in the novel construction, combination and arrangement of parts 35 substantially as hereinafter described and more particularly defined by the appended claims, it being understood that such changes in the precise embodiment of the herein described invention may be made as come 40 within the scope of the claims.

In the accompanying drawings I have illustrated two complete examples of the physical embodiment of my invention constructed according to the best modes I have 45 so far devised for the practical application of the principles thereof, and in which

Figure 1 is a view taken through a portion of the stitcher machine equipped with my novel form of feeding mechanism, parts 50 being in elevation and parts in section to more clearly illustrate the same.

Fig. 2 is a view looking at my feeding mechanism on the plane of line 2—2 of Fig. 1, a part being broken away and in section.

Fig. 3 is a view similar to Fig. 1 of a

slightly modified construction of feeding mechanism, and

Fig. 4 is a plan view taken on the plane indicated on the line 4—4 of Fig. 3.

In book-stitching machines, the collected groups of signatures are usually fed past an alining device after which they are taken by the stitcher feed past the stitchers and as the alining device forms no part of the present application only the feeding mechanism will be described. The groups of signatures 5 from the conveyer (not shown) are fed over an inverted V-shaped saddle designated generally by the numeral 6. Stitchers 7 are secured to the frame 8 in 70 spaced relation for coöperating with clencher mechanisms 9 to insert the staples in the books or groups of signatures as they pass over the saddle 6, but as their construction and the manner of attachment to the machine forms no part of the present invention further detailed description thereof is deemed unnecessary.

The signature feeding mechanism for carrying the books or groups of signatures 80 along the saddle 6 to the stitchers 7 and then from the stitchers to the delivery mechanism (not shown) consists of a longitudinally movable feed bar 10 slidably mounted in a recess 11 in one of the sides of the saddle, 85 means for moving the bar, and means for pressing the groups of signatures 5 against said bar and moving them in toward the stitchers before being stitched and from the stitchers toward the delivery mechanism 90 after being stitched.

The means for moving the feed bar 10 consists of a lever 12 having its upper end pivotally connected to one end of a link 13, which link is pivotally connected at its other 95 end to a bearing bracket 14 secured to the under side of the feed bar, said lever has its lower end pivotally mounted and is adapted to be reciprocated as illustrated and described in Letters Patent No. 1,351,231, issued to me August 31, 1920.

Referring now more particularly to Figs. 1 and 2, the means for pressing the signatures against the bar 10 consists of a plurality of signature engaging fingers or plungers 15, each having its shank 16 slidably mounted within a retaining housing 17 and having coiled therearound and confined within the housing 17 an extensible spring 18 normally urging the signature engaging fin- 110

- ger 15 to engagement with the groups of signatures. The downward movement of the finger 15 under action of the spring 18 is limited by means of a stop pin 19.
- 5 The housing 17 is secured to a bar 20 which is vertically slidably mounted as will be later described and said bar is normally urged upwardly to its limit of movement by means of a retractile spring 21 so that 10 the fingers 15 of the signature engaging members will be disengaged from the groups of signatures. The means for engaging the signature engaging members with the groups of signatures consists of a rock 15 shaft 22 journally mounted in the frame 8 and having fixed thereto the lower ends of a plurality of arms 23 having rollers 34 journaled in their upper ends and engaging the upper edges of the bar 20.
- 10 The rock shaft 22 is adapted to be oscillated by means of suitable mechanism as described in said Letters Patent No. 1,351,231, issued to me August 31, 1920, and is connected with said mechanism by means 25 of an arm 25. When the arms 23 are rocked to the left in reference to Fig. 1, the bar 20 will be moved downwardly against the action of the springs 21 and the members 15 engaged with the group or groups of signatures to bind the same between them and the bar 10 and means are employed for moving said bar 20 conjointly with the rod 10 to feed the signatures to the stitchers or from the stitchers after same have been 30 stitched.
- The means for moving the bar 20 conjointly with the bar 10 consist of a slide bar 26 slidably mounted in guideways 27 in a support 28, said slide bar being reciprocated by a lever 29 connected thereto at its upper end by means of a link 30 and an arm 31 depending from the slide bar 26. The lever 29 is rocked or reciprocated conjointly with the lever 12 and thus the bar 40 45 20 and bar 10 are conjointly moved to and from the stitcher. The bar 20 is secured to the slide bar 26 by means of a plurality of securing members 32 which pass through an aperture 33 in said bar 20 and engage the slide bar 26 and is normally urged to its upper limit of movement by the springs 21 having their upper ends secured to the slide bar 26 and their other ends secured to the bar 20, see Fig. 1.
- 50 55 In that form of my invention depicted in Figs. 3 and 4 in the place of the plungers 15 I employ the plurality of medially pivoted finger members 34 mounted upon pins 35 carried directly by the slide bar 26, each 60 having a signature engaging portion 36 normally urged to engage with the groups of signatures by means of a retractile spring 37 having one end secured to the slide bar 26 and its other end secured to the finger 65 member near its end remote from its signa- ture engaging portion. As in that form of my invention designated in Figs. 1 and 2, the finger members 34 are reciprocated with the slide bar 26 and the means for disengaging the ends 36 of said finger members 70 from the groups of signatures consist of a reciprocally mounted bar 38 along the under side of which tracks an idler wheel or pulley 39 carried by each finger in its upper end and the rod 38 is adapted to be rotated 75 by means of a rocking lever 40 connecting with suitable rocking means, not shown.
- In this form of my invention the rod 38 when rocked to the left with reference to Fig. 4, is depressed by means of cams 41 80 formed thereon and engaging fixed arms 42 carried by the support 28 of the pulleys 39 and disengage the ends 36 from the signatures.
- During the rearward movement of the 85 bars 10 the stitching mechanism 7 is adapted to operate and during this movement the plungers 15 or the fingers 34 are held from engagement with the groups of signatures. In that form of my invention depicted in 90 Figs. 1 and 2 the plungers 15 are disengaged from signatures by movement to the right of the arms 23, with reference to Fig. 1, which permits the springs 21 to move the bar 20 upwardly and the fingers 34 depicted in Figs. 3 and 4 are disengaged by means of a rocking lever 40 engaging cams 41 with the arms 42 depressing the bar 38 and moving the fingers 34 against the action of springs 37. When the bars 10 and 26 100 have reached their entire rearward limit of movement the plungers 15 or the fingers 34 are permitted to engage with the groups of signatures and as said bars begin their movement toward the stitchers said plungers 105 or fingers engage the next group of signatures and the group which has just been stitched will be moved toward the delivered mechanism and another group be positioned beneath the stitchers. 110
- What I claim as my invention is:
1. The combination with the signature holder of a book stitching machine, of signature feeding mechanism comprising a pair of devices adapted to engage the opposite sides of the signatures, means to move said devices simultaneously relative to said holder, and means to move one of said devices relative to the other for the purpose described. 115
  2. The combination with the signature holder of a book stitching machine, of signature feeding mechanism comprising a member slidably mounted on said holder and adapted to engage one side of the signatures, a bar mounted in the frame of the machine and slidably with respect to said holder, a device mounted on said bar and co-operating with said member to grip the signatures, and means to move said member and said bar si- 120 125 130

multaneously relative to said holder for the purpose described.

3. The combination with the signature holder of a book stitching machine, of signature feeding mechanism comprising a member slidably mounted on said holder and adapted to engage one side of the signatures, a bar mounted in the frame of the machine and slidable with respect to said holder, a 10 device mounted on said bar and coöperating with said member to grip the signatures, means to move said bar toward or away from said member, and means to move said member and said bar multaneously relative to 15 said holder for the purpose described.

4. The combination with the signature holder of a book stitching machine, of signature feeding mechanism comprising a member slidably mounted on said holder and 20 adapted to engage one side of the signatures, a bar mounted in the frame of the machine and slidable with respect to said holder, a device yieldably mounted on said bar and co-operating with said member to grip the signatures, and means to move said member and 25 said bar multaneously relative to said holder for the purpose described.

5. The combination with the signature holder of a book stitching machine, of signature feeding mechanism comprising a member slidably mounted on said holder and 30 adapted to engage one side of the signatures, a bar mounted in the frame of the machine and slidable transversely and longitudinally 35 with respect to said holder, a device mounted on said bar and coöperating with said member to grip the signatures, means to move said bar laterally toward or away from

said member, and means to move said member and said bar multaneously relative to 40 said holder for the purpose described.

6. The combination with the signature holder of a book stitching machine, of signature feeding mechanism comprising a member slidably mounted on said holder and 45 adapted to engage one side of the signatures, a bar mounted in the frame of the machine and slidable transversely and longitudinally with respect to said holder, a device yieldably mounted on said bar and coöperating 50 with said member to grip the signatures, means to move said bar laterally toward or away from said member, and means to move said member and said bar multaneously 55 relative to said holder for the purpose described.

7. The combination with the signature holder of a book stitching machine, of signature feeding mechanism comprising a member slidably mounted on said holder and 60 adapted to engage one side of the signatures, a bar mounted in the frame of the machine and slidable transversely and longitudinally with respect to said holder, signature gripping devices mounted on said bar, means for 65 normally holding said bar so that said devices are out of engagement with the signatures, means for moving said bar toward the signatures to bring said devices into engagement therewith, and means for multaneously moving said member and said bar relative to said holder to carry the signatures over said holder. 70

In testimony whereof I affix my signature.

MARTIN CHRISTENSEN
